UNITED STATES PATENT OFFICE.

NATHANIEL L. BARMORE, OF CHICAGO, ILLINOIS.

DESIGN FOR A NAME-PLATE FOR BURIAL-CASKETS.

42,079.

Specification for Design.

Patented Jan. 9, 1912.

Application filed October 26, 1910. Serial No. 589,264. Term of patent 14 years.

To all whom it may concern:

Be it known that I, NATHANIEL L. BARMORE, a citizen of the United States, residing at Chicago, in the county of Cook and State of Illinois, have invented a new, original, and ornamental Design for a Name-Plate for Burial-Caskets, of which the following is a specification, reference being had to the accompanying drawing, forming a part thereof.

The figure is a plan view of a name plate for burial caskets, showing my new design.

I claim,

The ornamental design for a name-plate for burial caskets, as shown.

In testimony whereof, I have hereunto signed my name in the presence of two subscribing witnesses.

NATHANIEL L. BARMORE.
